CLAIM

The ornamental design for a combined stop and tail lamp lens, as shown and described.

DESCRIPTION

FIG. 1 is a top plan view of a combined stop and tail lamp lens showing my new design.

FIG. 2 is a fragmentary sectional view on an enlarged scale taken along the line 2—2 in FIG. 1.

FIG. 3 is a fragmentary sectional view on an enlarged scale taken along the line 3—3 in FIG. 1.

FIG. 4 is an end view thereof on a reduced scale.

FIG. 5 is a side view thereof on a reduced scale.

The faceting and screw apertures which would normally appear through the lens are omitted in FIGS. 4 and 5 for convenience of illustration.
